UNITED STATES PATENT OFFICE

2,049,873

COPY HOLDER

Lewis W. Shafer, Cincinnati, Ohio

Application May 13, 1933, Serial No. 670,929

11 Claims. (Cl. 24—66)

My invention relates to paper clamping devices to be used, in connection with copy holders, to hold turned pages of stenographers' note books or multiple page forms, on what I choose to call 5 the "fly past principle". By the term "fly past principle", I mean that the pages of a stenographers' note book or multiple page form are caused to "fly past" an abutment by a flip of the wrist, and are subsequently held against said abutment 10 from the rear.

Devices for holding books and sheets from which copy is made on a typewriter are old and well known. One form of device which has been considerably exploited commercially is shown in 15 the Griffith Patent No. 1,014,646, to which reference is hereby made.

It is the object of my invention to provide a 20 copy holder in which a copy plate, adjustable clamping device and line indicator are so mechanically interconnected that the labor of inserting the various types of copy work is reduced to a minimum. The inserting of the stenographic note book in particular is simple and can be 25 readily accomplished even if the operator only uses one hand.

Another object of my invention is to provide 30 supporting brackets composed of upwardly sloping arms with swivels at either end and so arranged that even though the supporting stand is located at the rear or side of a desk the arms will carry the holder to any position required. The device is not attached to the machine or typewriter with which it is used. The arms also provide a quick way to remove it to its out of use 35 position which does not interfere with the opening and closing of the typewriter desks. The arm construction also makes it possible to read at the position best suited to the eyes of the user and at the angle which will provide the best light on the copy.

Another object of my invention is the provision 40 of a supporting post for the supporting arms which is held in position by either a clamp attached to the top of a desk or a floor stand of heavy cast iron. On the latter the supporting post extends all the way to the base located on the floor and is guywired against vibration by wires running from the supporting arm to the legs of the base. The post is also equipped with 45 a collar which can be localized at various positions giving the holder the necessary height adjustment.

Another object of my invention is the provision 50 of a line indicator pivotally mounted in such a way that it can be localized vertically along the

extreme edge of the holder, when the work being copied does not require a horizontal guide. The combination of the pivot principal and the slider on which it is mounted makes it possible to quickly swing the line indicator to its horizontal position and move it to any position desired without removing your hand from the slider. This makes it possible to quickly place the indicator to whatever position the work requires, even though it may be the middle or lower position on the sheet 10 being copied. The slider is also equipped with an adjustable clamping support for the line indicator so that the alignment of the indicator can be varied if necessary. A line by line movement of the indicator is provided for by a knob 15 conveniently located at the bottom of the copy plate.

Another object of my invention is the provision 20 of a copy holder with a flapper clamp that extends above the upper end thereof to hold the upper portion sheets of a stenographic notebook or multiple page form. The turning of a page is then almost automatic as a slight pressure and quick release of the page against the flapper plate carries the page past the friction grips where 25 it is held in its correct position. The flapper clamp has a height adjustment on the rear of the copy plate so it can be localized at a position which will permit the pages to flip past the friction grips with but a slight indentation of the 30 flapper regardless of variation in size of notebook or form being copied. This constitutes an important feature of the present invention.

It is a purpose of my invention to have one 35 model of copyholder, the front plate of which can be installed in any position relative to any type of office equipment, yet not be attached to the equipment itself. The copy plate, its vertical swivel joint, the supporting arms and floor type supporting post, are so mechanically interconnected that this result can be obtained and the holder will be unaffected by any vibration which might be caused by the above mentioned office equipment.

The main object of my invention is the provision 45 of a flapper clamp to hold the upper portion of the sheets of a stenographic note book or multiple page form. With this device, the turning of the page is almost automatic, as it is only necessary to flip the page to its full 50 height above the bound or clamped position of the multiple page form, and apply a finger pressure against the page as it rests against the flapper. A movement of the flapper backwardly will then carry the turned page past the friction grips, 55

where a quick release of the hand will leave it held in its correct, out of the way position. The flapper clamp may be mounted adjustably, in which case it will be possible for the page to be flipped past the friction grips with but a slight indentation of the flapper, regardless of the size of the multiple page form being copied.

The above objects and other objects to which reference will be made in the ensuing description, I accomplish by that certain combination and arrangement of parts of which I have shown my preferred embodiment.

Referring to the drawings:

Figure 1 is a front elevation of the copy holder in position suitable to receive a stenographer's note book.

Fig. 2 is a rear elevation of the copy holder.

Fig. 3 is a sectional view taken along the lines 3—3 in Fig. 2.

Fig. 4 is a sectional view of the copy holder as it would appear along the lines 4—4 in Fig. 1, the position of a stenographer's note book being given in dotted lines.

Fig. 5 is a detailed sectional view showing the operation of the sheet clamping mechanism.

Fig. 6 is a perspective view of the floor stand.

Referring first to Fig. 1, I have illustrated the channel base 1 having thumb screws 2 by which the base member may be clamped to the projecting ledge of a table or desk top.

The base member has a threaded boss 3 within which a pedestal rod 4 is secured. On the pedestal rod there is a collar 5 having a thumb screw 6 by which the collar may be adjusted at a desired position on the pedestal. If it is desired, a floor stand may be used (Fig. 6) with an ordinary floor spider 70 and the pedestal rod 4 screwed into this spider and held rigid by means of the guy-wires 71. Of course in this case the pedestal rod 4 will be long enough to support the copy holder in the operator's field of vision.

The lower arm forming the swiveled support for the copy holder has an apertured boss 7 which slidably and rotatively engages the pedestal rod 4. The lower arm is indicated at 8 and its upper end is provided with an apertured boss 9. A yoke member 10 of a second pivoted bracket arm 11 engages the boss 9, and a bolt 12 having a nut 13 extends through the yoke and boss providing a pivotal connection therebetween.

The copy supporting plate 14 has an outwardly flanged lower edge 15 and the sides of the plate are bent back in the form of channels 16. A reinforcing plate 17 extends across between the channels 16 of the copy supporting plate and a bracket piece 18 is bolted to the reinforcing plate 17. A yoked boss 19 receives a flat boss 20 of a yoke 21, which engages an apertured boss 22 formed at the upper end of the arm 11 and a bolt 23 and nut 24 provides a pivotal connection between the yoke 21 and the boss 22.

The bracket 18 has a slotted portion 25. The holder for the sheets or note books is adjustably mounted on a sliding plate 26 which is held in the slotted portion 25 by means of a thumb nut 27.

Frame arms 28 extend upwardly from the plate 26 beyond the upper end of the copy supporting plate 14 and a bar 29 is adjustably mounted in the down-turned upper ends 30 of the frame members 28, being secured therein by means of screws 31. The arm 29 has narrow tubular collars 32 on it to provide a frictional grip on the sheets or copy book being held in the holder. A bar 33 extends across the frame 28 and on this bar 33

there is pivoted a pressure board or clamping plate 34 which extends above the upper end of the copy supporting plate 14 and is movable independently thereof into and out of clamping position. Extensions 35 extend down from the lower edges of the plate 34. They exert spring action against the base of the arm structure 28 to urge the plate 34 forwardly so that sheets which extend above the upper end of the relatively fixed copy holding plate 14, may be held between the plate 34 and the narrow rollers 32 and will maintain their position accordingly.

Secured to one side of the copy holding plate 14, there is a square bar 36 on which a slider 37 operates. A thumb wheel 38 is mounted in the boss 39 at the lower end of the bar 36, and carries a sprocket 40 which a chain 41 engages. The chain 41 passes over a loose sprocket 42 journaled at the top end of the bar 36, and is secured at both of its ends to the slider 37. Fastened to the slide there is an arm 42 which is held resiliently against the bar 36 by the pressure of the coil spring 43. This arm prevents the slider from vibrating on the bar 36.

By turning the wheel 38, the slider 37 is moved up and down along the bar 36. On the slider there is a circular rim 43 which houses a disc 44. The position of the disc is fixed but the rim 43 may rotate on it, its position being determined by the position of a thumb screw 45 in a slot 46 in the rim member 43, and screwed into the disc 44.

A pin 47 extends through an aperture 48 in the disc 44 and a spring 49 held by a nut 50 on the exposed end of the pin 47 provides a resilient mounting for the pin.

Extending from a hole in the pin 47, a preferred type of line indicator consisting of a rod 51 carrying an apron shaped guide 52 is shown. The rod 51 extends through both sides of the pin 47 and registers with semi-circular slots 53 in the annular edge of the rim 43, so that the position of the line indicator is determined by the position of the rim 43, as determined by the adjustment of the thumb screw 45 in the slot 46.

The particular object of the adjustability of the line indicator is so that where the words of the copy mounted on the copy plate extend diagonally across the sheet instead of horizontally, the line indicator may be adjusted to follow the diagonal lines of copy.

In Figs. 4 and 5 the ease of mounting a stenographer's note book is illustrated. The book which is indicated in dotted lines at A, in Fig. 4, is supported in place on the copy supporting plate 14 to properly coat with the line indicator, the lower edge of the book resting against the flange 15 of the copy supporting plate. The upper leaves of the book are pressed with the fingers against the holding plate 34, and a slight pressure with the tips of the fingers causes the upper ends of the pages to slip in between the upper edge of the plate 34, and the narrow rollers 32, carried on the rod 29. The pressure thus exerted by the operator on the turned page is effective to move the holding plate 34 rearward against its spring pressure independently of the copy holding plate 14 and that part of the book which is supported thereby. As soon as the operator releases pressure on the turned page which extends above the upper edge of the copy holding plate 14, the spring pressed plate 34 will press said page against the holding bar. It will be understood that the turning and holding of the page is effected with a single movement of the hand of the operator.

While I have shown the thumb wheel 38 for moving the line indicator, it will be quite obvious that a ratchet arm for moving the line indicator in a series of spaced movements may be employed, 5 as such a means for moving the line indicator relative to the copy plate is old and well known in the art.

Having thus described my invention, what I claim as new and desire to secure by Letters Patent is:—

1. In connection with a copy holder, a paper clamping device for turned pages comprising a rigid abutment and a hinged plate lying in a plane other than that of the pages to be clamped and resiliently urged against said abutment. 15

2. In connection with a copy holder, a paper clamping device for turned pages comprising a rigid bar and a hinged plate lying in a plane other than that of the pages to be clamped and resiliently urged against said bar, said bar being 20 in front of said plate and determining the position of said plate.

3. A paper clamping device for turned pages, to be used in connection with a copy holder, comprising a rigid abutment and a cooperating clamping member resiliently mounted in a plane other than that of the pages to be clamped, for movement in an arc away from said abutment. 25

4. A paper clamping device for turned pages, 30 to be used in connection with a copy holder, comprising a rigid abutment and a cooperating clamping member resiliently mounted in a plane other than that of the pages to be clamped, for movement in an arc away from said abutment, 35 said abutment comprising a horizontal bar and said clamping member comprising a horizontally hinged plate, both of which are fastened to the same support.

5. A paper clamping device for turned pages, 40 to be used in connection with a copy holder, comprising a rigid abutment and a cooperating clamping member resiliently mounted in a plane other than that of the pages to be clamped, for movement in an arc away from said abutment, 45 said abutment comprising a horizontal bar and said clamping member comprising a horizontally hinged plate.

6. A paper clamping device for turned pages, 50 to be used in connection with a copy holder, comprising a rigid abutment and a clamping member mounted in a plane other than that of the pages to be clamped, so as to be resiliently urged against said abutment, said abutment determining the forward position of said member, and the resilient mounting of said member permitting a movement thereof in an arc away from said abutment, 55 said device being adjustably mounted on said holder.

7. A paper clamping device for turned pages, to be used in connection with a copy holder, comprising a rigid abutment and a hinged plate resiliently urged against said abutment, the said resilience being provided by strips of resilient material firmly affixed to the back of said hinged plate so as to normally lie in close contact therewith, said strips extending beyond the said hinged portion and bearing against a fixed portion on said copy holder. 10

8. A paper clamping device for turned pages, to be used in connection with a copy holder, comprising a rigid abutment and a hinged plate, the said plate having strips of resilient material firmly affixed on its rear face so as to normally lie 15 in close contact therewith, the said strips being longer than said plate and bearing against a fixed portion of said copy holder so as to resiliently urge the said plate forwardly against said abutment. 20

9. A paper clamping device for turned pages to be used in connection with a copy holder, comprising a spring pressed clamping plate pivoted on the copy holder for movement relatively to the copy supporting portion thereof, and a holding 25 member arranged to receive between it and said clamping plate a turned sheet of a note book supported in place on said copy holder and to hold said turned sheet by the pressure exerted between the clamping plate and holding member. 30

10. A paper clamping device for turned pages to be used in connection with a copy holder, comprising a substantially upright spring pressed clamping plate extending above and pivoted on the copy holder for movement relatively to the 35 copy supporting portion thereof, and a holding bar arranged above the copy holder to receive between it and said clamping plate a turned sheet of a note book supported in place on said copy holder and to hold said turned sheet by the pressure exerted between the clamping plate and holding bar. 40

11. A paper clamping device for turned pages to be used in connection with a copy holder, comprising an upright clamping plate pivoted for independent movement on and extending above the copy holder in a position to coact with a turned sheet of a note book supported by the copy holder, a holding bar carried by said copy holder and arranged above it and in front of said clamping 50 plate in a position to receive behind the clamping bar a turned sheet of a book supported by the copy holder and spring means that tend to move said clamping plate forward in contact with said holding bar and to clamp the turned sheet or 55 sheets of the book between said clamping plate and holding bar.

LEWIS W. SHAFFER.
